UNITED STATES PATENT OFFICE.

JOSEPH BOMGARDNER, OF BEREAL, OHIO, ASSIGNOR TO BOMGARDNER
LOWERING DEVICE COMPANY, OF CLEVELAND, OHIO.

BURIAL-CASKET-LOWERING DEVICE.

SPECIFICATION forming part of Letters Patent No. 689,847, dated December 31, 1901.

Application filed February 6, 1901. Serial No. 46,165. (No model.)

To all whom it may concern:

Be it known that I, JOSEPH BOMGARDNER, a citizen of the United States of America, and a resident of Berea, in the county of Cuyahoga and State of Ohio, have invented certain new and useful Improvements in Burial-Casket-Lowering Devices, of which the following is a specification.

My invention relates to improvements in devices which are employed for lowering burial-caskets into graves; and the objects of my improvement are, first, to provide a device for such purposes which may be conveniently adjusted for caskets or graves of various dimensions; second, to render such devices compact, neat, and constructive in appearance, and, third, to reduce the act of lowering caskets to the least ostensive manipulation. I attain these objects in a device constructed substantially as shown in the accompanying drawings, in which—

Figure 1 represents a part plan and part sectional view of the device above referred to. Fig. 2 is a part face and part sectional view of said device, illustrating the transverse part A thereof as seen from the outside, covers removed. Fig. 3 illustrates an inner face view of said part A detached. Fig. 4 represents a partial horizontal sectional view of a corner portion of said device. Fig. 5 represents a side view of said corner portion. Fig. 6 is a face and part sectional view of the same. Fig. 7 represents a horizontal sectional view of the right-hand terminal of said part A. Fig. 8 represents a part face and part sectional view of the part A, coverings detached. Fig. 9 illustrates a vertical sectional view on line 11. (See Fig. 8.) Fig. 10 is a transverse sectional view on line 2 2. (See Fig. 1.) Fig. 11 is an exterior view to Fig. 8. Fig. 12 is a partial horizontal sectional view of details hereinafter referred to. Fig. 13 is a transverse sectional view of the same. Fig. 14 is another transverse sectional view on line 3 3. (See Fig. 1.) Fig. 15 is a transverse sectional view on line 4 4. (See Fig. 1.) Fig. 16 is a longitudinal view of a key-lever or wrench used in connection with said device. Fig. 17 is an end view of said wrench. Fig. 18 is a face view of a buckle used in connection with the casket-carrying

bands of this device, and Fig. 19 is a side view of the same. Figs. 2, 3, 15, 16, and 17 are shown enlarged with regard to Fig. 1, and Figs. 4, 5, 6, 7, 8, 9, 10, 11, 12, 13, 14, 18, and 19 are drawn on a still larger scale.

Like letters of reference denote like parts in the drawings and specification.

Substantially the device consists of an adjustable rectangular frame carrying in and by its longitudinal poles B B' a series of transversely-extending belts C C C, upon which the caskets are placed. To render such frame adjustable (telescoping) transversely as well as longitudinally and to provide for efficient convenient means to manipulate said belts, therein rests the spirit of my invention.

The frame comprises the head structure A, the foot structure D, and the longitudinal poles B B'. (See Fig. 1.)

The head structure consists of the girders A' A² and the foot structure of the bars D' D². Attached to the girders A' A² in any suitable manner are the tubular poles B B, while the bars D' D² carry extensions E E' for telescoping connection with said poles, as seen in Figs. 1, 4, 5, and 6. Simply to reduce friction and weight polygon tubular form is preferred for the said extensions E E'. In the drawings octagon form is indicated. (See Figs. 5 and 6.) Other polygon forms, however, may be employed with like result—namely, that of reducing friction in sliding these extensions into and out from the poles B B'. Extending from and through the girders A' A² into the poles are the rollers F F', said rollers being journaled or guided within the poles, substantially as shown at a a'. (See Figs. 1, 7, and 9.) At proper intervals said rollers are slotted, as at b b', (see Figs. 1, 12, 13, and 14,) for reception or attachment of the terminals of the bands or belts above referred to. Arranged within the girders A' A² is the mechanism for turning said rollers to manipulate said belts or bands. A friction band-wheel is secured to each of the rollers G G', Figs. 2, 7, 8, and 9. Also sprocket-wheels H and an endless chain I are provided for effecting simultaneous uniform rotation of said rollers, so that an equal amount of bandage can be wound up onto said rollers or unwound from said rollers, as conditions may

require. Furthermore, in connecting the rollers by gearing substantially as shown one need turn but one of the rollers for winding up the bands or belts. Also the brake of only 5 one of the band-wheels need be released in order to effect unwinding of the belts in the lowering of the casket lying upon said belts. The idler-wheels J J', around which the chain is wound, permit of contraction and 10 expansion of the girders forming the end frames as different-sized caskets and graves may require. Said idler-wheels are loosely mounted upon pivots, (see sectional view of Fig. 7,) and the pivots project from the plates 15 K K'. (See Figs. 2, 7, 8, and 10.) The plates in turn form the terminals of the branches L L', of which the heads c c' form a reinforcement for connection of the respective girders and poles. (See Figs. 7 and 9.) The girders 20 proper are of channel form, one, A', telescoping into the other, A². (Most plainly seen in Fig. 10.) The corner portions of said girders are covered by means of caps d, and attached to each of the caps d is a leaf e of 25 proper length to inclose the entire mechanism within said girders. (See Sheet III of the drawings.) Likewise are the bars D' D² of the foot structure of channel form, telescoping one into the other. (See Figs. 1, 30 4, 5, and 6.) A series of holes are placed in the top flange of the telescoping girder A² as well as in that of the bar D². Said holes are analogously positioned to afford engagement with the pin of a spring-latch M, of which 35 one is secured to the outer girder and outer bar. (See Figs. 1, 2, and 3.) With such locking devices one is enabled to set and secure the frame for and at different widths as locations and conditions may require. A clamping 40 device f at the terminal of each of the poles enables adjustment and fixing of the frame in longitudinal direction. (See Figs. 1, 5, and 6.) To prevent accidental disengagement of the extensions E E' from the 45 poles, a pin or screw g is extended from the outside through a slot g' of said extensions, and the slot-terminal stops the extensions short of being drawn entirely from out of the poles. As shown, the foot structure is extended but partially from out or away from 50 the poles; also, transversely the frame is but partially expanded. (See Fig. 1, 2, and 3.)

By means of the idler-wheels compensation is afforded for the chain in expanding and 55 contracting the frame. Beginning from the top of the sprocket-wheel H to the right said chain runs behind the idler-wheels to the bottom of the sprocket-wheel upon the left-hand roller; from the top of said wheel connection 60 is had with the top of idler J, which moves with the left-hand girder; from the bottom of the idler J the chain runs over the top of the idler J', which is a stationary element of the girder A², and from the bottom of the last-named idler J' the chain returns to the bottom of the first-named sprocket-wheel. (See 65 Figs. 2, 7, and 8.) To whatever extent the

roller sprocket-wheels are drawn from each other in the same ratio do the idler-wheels approach each other, and for this reason the 70 chain allows of expansion and contraction of the girders, and yet affords for any and all positions an invariable operative medium for transmission of motion from one roller to the other. The projections h h' simply serve as 75 guard or guide plates for the chain in the manner as shown.

Each of the friction-wheels G G' is lined with leather or other suitable material to afford increased friction for the straps or bands 80 N N', which encircle said wheels. The straps in turn are united by a screw-threaded bridge i, having a spindle j, extending therethrough. Intermediate the spindle and the top of the wheel is a leather-lined block k, which affords 85 resistance and a bearing for the spindle in applying brake-power unto said wheels.

When the bands C are wound up and the brakes are set—that is, when the straps N N' are drawn tightly around the wheels—then a 90 casket or other load can be safely held in suspended condition by said bands. Preferably only one of the brakes is manipulated for lowering caskets into graves—say the one to the right.

With the key or wrench O the operator is 95 enabled while in erect position to manipulate the device as presently described. As shown, the right corner is where the device is adjusted and operated from, since the roller leading from said corner and having the wheel H is equipped for the winding up of the bands as well as for lowering same, either directly by means of the crank-handle l or indirectly by means of the key or wrench O.

By means of the crank-handle l the bands 100 can be wound up after the terminals of said bands are inserted into the slots b b' of the rollers, (see Figs. 13 and 14,) the latter figure showing a series of slots b, which are preferably provided in the roller within the pole B in order to assure the appearance of one or the other of said slots within reaching distance of the opening or openings m when the slots in roller F' appear in alignment with the 105 openings m' of the pole B'.

The fact that the left-hand side of the frame telescopes into the right side thereof requires the branch L to be offset from its girder-wall in order to allow the left girder to pass between the right-hand girder-wall and its branch. (See Figs. 7 and 10.) Such conditions determine the above-described run of the endless chain and the particular relation of the loops between the idler-wheels to that of the 115 strings of chain leading to and from the sprocket-wheels.

In adjusting the frame—that is, in pulling the left-hand side from out of the right-hand side—it is evident that the right-hand 120 sprocket-wheel H and the idler-wheel J' remain stationary while the sprocket-wheel and idler-wheel of the left-hand girder, so to say, roll upon the chain and either lengthen or

shorten the loops between the idlers to compensate for the expansion or contraction of the sprocket-wheels. If in the adjustment of the frame the roller F turns while the roller F' remains stationary, as might happen were there only a single slot in said roller, said slot would not appear within reach from the openings in the pole B. Therefore a plurality of slots are placed along and around the roller F, so that one or the other set will be within reach of the opening m in order to enable insertion or attachment of the bands onto the roller F no matter to what width the frame may be adjusted.

15 Instead of having for each band in the right-hand roller only one slot to four slots in the left-hand roller there may be more than one slot in the right-hand roller and less than four slots in the left-hand roller. Two or three slots 20 for each band in each roller would afford equal and ample opportunity for attaching the terminals of the bands with ease, regardless to the adjustment of the frame. When there is no load (casket) resting or lying 25 upon the bands, then one is enabled to wind up the bands by means of the crank-handle l. With a casket lying on the bands, however, the wrench or lever O is required to enable a rotation of the rollers or raising of the 30 casket, should such operation become necessary or desirable. Since there is no room for turning a lever completely around when the frame is lying over an open grave so near the ground, I provide, in connection with the 35 sprocket-wheel H, the ratchet-wheel n and a series of cams o, as seen in Figs. 8, 9, and 11. Furthermore, pivoted to the inner wall of the cap d is a pawl p, engaging said ratchet-wheel and locking the rollers in any desired position. 40 For raising a casket the head q of the lever O is inserted into the tube far enough so that the arms r thereof engage the face sides of said cams, whereupon the rollers can be turned to the extent of about a half-circle 45 at any one engagement of the lever O. During the exchange of the arms r from one pair of cams to the other it is the pawl p which prevents the wheel n from turning backward. A casket can therefore be held in suspension at 50 any suitable height as long as the pawl p engages the wheel n or is allowed to drop into the notches thereof. As shown in Figs. 10 and 11, the arm p' of said pawl extends through the cap d within reach of the latch S, which latch 55 when turned directly over said arm holds the pawl from out of engagement of the ratchet wheel.

In the ordinary use of this casket-lowering device the preliminary operation consists in 60 the adjustment of the frame to suit both the location and casket. When this is done, then the bands C are wound up until they stretch in about a horizontal position across the frame, or from pole to pole, whereupon the 65 brakes are tightened to insure a free support of the casket to be laid thereon. At proper

time the spindles or screws j are loosened and the casket descends in the least ostensible manner. When the casket has reached the ground, then it is the buckle P (see Figs. 18 70 and 19) which automatically separates the bands in under the casket and allows of the withdrawal of said bands. As shown, said buckle is of open-loop form, and being attached to the link t' of the right-hand band portion the hook u engages the link t of the left-hand band portion and unites said band portions as long as the bands are in suspended condition; but as soon as the ledge v strikes the bottom of the grave then the 80 link becomes released from the hook u and the bands can be drawn from under the casket. If the bands are used without a buckle, then one or the other terminal thereof may be disconnected from the roller to admit 85 of withdrawing of said bands. For transportation this frame is contracted as close as possible both longitudinally as well as transversely. The spring-latches in that instance interlock into the last hole of the telescoping 90 girder and bar. Furthermore, the key or lever is disposed of by being inserted into one of the tubular rollers and retained therewith, substantially as shown in Fig. 15, which shows a spring-guard w in connection with the left 95 girder-cap, sprung into which is the head q of said wrench for the purpose of securing same in place—namely, within the tube F.

What I claim, and desire to secure by Letters Patent, is—

1. In a casket-lowering device, the combination of a telescoping end girder, having two tubular poles leading therefrom; rollers mounted within said poles of a length less than the length of said poles; bands connecting said rollers; means carried by said girder and operable from a single point for imparting movement to said rollers, said means being adjustable with the telescoping movement of said girder; and a foot member telescopically connected to said poles, said foot member being adjustable to correspond with the adjustment of said end girder.

2. In a casket-lowering device, the combination of a telescoping end girder having a 115 box-like configuration, and having two tubular poles secured to the inner face of the girder; rollers mounted within said poles, said rollers extending within said box-like girder; bands connecting said rollers; means 120 carried by said girder and said rollers for imparting movement to the rollers, said means being adjustable with the telescoping movement of said girder; and a foot member telescopically connected to said poles, said foot 125 member being adjustable to correspond with the adjustment of said end girder.

3. In a casket-lowering device, the combination with two rollers in parallelism, carrying connecting bands; and an adjustable 130 frame for regulating the distance between said rollers; of driving means located solely

at one end thereof and in alinement therewith, said means including a compensating device.

4. In a casket-lowering device, the combination with two spaced rollers carrying connecting-bands; and means for adjustably regulating the distance between said rollers; of a gear located at one end of each of said rollers; and connections between said gears for imparting simultaneous movement thereto, said means including a compensating device, adapted to maintain the operative connection between said gears irrespective of the relative positions of said rollers.

15 5. In a casket-lowering device, the combination with a telescoping end girder; and two spaced rollers carrying connecting-bands; of a gear located at one end of each of said rollers; and a sprocket-chain connecting said 20 gears; and a coöperating compensating device, whereby said chain will be held in operative connection with said gears during the telescoping movement of said girder.

6. In a casket-lowering device, an end girder 25 formed in two parts, arranged to telescope; rollers located at the outer ends of said parts, each roller having a drive-wheel; an idler-wheel connected to each of said parts; and a drive-chain operatively connected to each of 30 said drive-wheels said chain passing over said idler-wheels.

7. In a casket-lowering device, an end girder formed in two parts arranged to telescope; rollers extending from the outer ends thereof, 35 each roller having a drive-wheel; an idler-wheel carried by each part, said idler-wheels being movable bodily with the parts during the telescoping movement, the two idler-wheels moving in a direction opposite the direction 40 of the telescoping movement; and a drive-chain operatively connected to each of said drive-wheels, said chain passing over said idler-wheels.

8. In a casket-lowering device, two spaced 45 rollers carrying connecting-bands; an adjustable frame for regulating the distance between said rollers; driving means located at one end of said rollers; and braking mechanism for each of said rollers, said mechanism 50 having a direct connection with the rollers.

9. In a casket-lowering device, two spaced

rollers carrying connecting-bands; an adjustable frame for regulating the distance between said rollers; driving means located at one end of said rollers; and braking mechanism for each of said rollers, said mechanism having a direct connection with the rollers and each mechanism being operable independently. 55

10. In a casket-lowering device, two spaced 60 rollers carrying connecting-bands; an adjustable frame for regulating the distance between said rollers; driving means located at one end of said rollers; and a friction-brake located in axial alinement and direct contact 65 with each roller.

11. In a casket-lowering device, two spaced 70 rollers carrying connecting-bands; an adjustable frame for regulating the distance between said rollers; driving means located at one end of said rollers; and a friction-brake for each roller located in axial alinement and direct contact therewith, said brakes being operable independently.

12. In a casket-lowering device, the combination with a telescoping end girder; of two spaced rollers, carrying connecting-bands, said rollers having their outer ends extending within said girder; a gear-wheel carried by the end of each of said rollers and adapted 80 to impart movement thereto; connections between said gear-wheels for imparting simultaneous movements thereto; a brake-band roller secured to each of said rollers; and a brake-band adapted to coöperate with said 85 brake-band roller. 75

13. In a casket-lowering device, band-carrying rollers; operable connections between said rollers for imparting simultaneous movement thereto; means removably insertible 90 within said connections for driving said rollers in one direction; and a pawl-and-ratchet device for normally holding said rollers against return movement, whereby said means may be moved in the opposite direction 95 without disturbing the position of the rollers.

Signed at Cleveland, Ohio, this 18th day of January, 1901.

JOSEPH BOMGARDNER.
